UNITED STATES PATENT OFFICE.

EDWIN F. KINGSBURY, OF RUTHERFORD, NEW JERSEY, ASSIGNOR TO EASTMAN KODAK COMPANY, OF ROCHESTER, NEW YORK, A CORPORATION OF NEW YORK.

SPOOL FOR PHOTOGRAPHIC FILM CARTRIDGES.

Original application filed January 21, 1921, Serial No. 438,888. Divided and this application filed September 6, 1921. Serial No. 498,932.

To all whom it may concern:

Be it known that I, EDWIN F. KINGSBURY, a citizen of the United States of America, residing at Rutherford, in the county of Bergen and State of New Jersey, have invented certain new and useful Improvements in Spools for Photographic Film Cartridges, of which the following is a full, clear, and exact specification.

10 This application relates to a spool for a roll film cartridge of the type commonly used in cameras, and is a division of my application, Serial No. 438,888, filed Jan. 21, 1921. In that application it was pointed out that when strip material, including photographically sensitized material and protective material, is wound upon a spool having end flanges with inwardly projecting marginal bosses that the bosses and the 15 material co-operate to prevent the fault known as edge fog, and this application is directed to the film spool which is thus used.

Reference will now be made to the accompanying drawing in all figures of which the 20 same reference characters designate the same parts and in which certain parts and dimensions are exaggerated for the sake of clearness:

Fig. 1 is a perspective view of a spool embodying my invention;

Fig. 2 is a section of one end of the spool having the photographic strip material wound thereon;

Fig. 3 is a sectional view of one end of a modified form of spool;

Fig. 4 is a sectional view of one end of another modified form of spool;

Fig. 5 is a sectional view of one end of one of my improved spools showing the resilient action of the flange which may exist when material is wound thereon.

My improved spool comprises a core which may be of any usual type, such as a wooden core, as shown at 1 in Figs. 3, 4, and 5, or 45 a metallic core, as shown at 2 in Fig. 2. At each end of the core is fixed by any of the customary methods end flanges 3. When used with a wooden core the flanges have inwardly turned tubular portions 4 which surround the ends of the core. The annular flanges are rigid with these. When a metal spool is used a metal disk is taken and the central part is struck out as shown at 6 to form a hub portion, and the ends of the tubular

core 2 are attached to the terminal disk by 55 any preferred method at 7. The extreme edge 5 of the disk lies in the same plane with the portion 7 of the end disk. In the case of the flange used with the wooden core, it preferably lies in the same plane with that 60 portion of the flange which lies adjacent the core at 8. From the core the flange is gradually inclined inwardly, as indicated at 9, reaching a maximum at 10, and then inclining quite rapidly outwardly again to the 65 extreme edge 5. There is thus formed at the margin an annular continuous abutment. If desired, the extreme edge may be only slightly turned back, as indicated in Fig. 3 at 11, or its final recurring may be omitted 70 entirely, as in Fig. 4, where the maximum point of inward bending is at the extreme edge, as indicated at 12.

The co-action between the strip material and the flange is fully explained in my co-pending application, and it is sufficient here to state that during winding the protective material 13, which is wider than the distance between the facing abutments, is slightly distorted or bent as it passes between these 75 abutments, and when wound upon the spool the compression of the strip material against the abutment holds it in rolled condition and constitutes a light lock at the ends of the roll, preventing the ingress of light to 80 the edges of the inner convolutions in which lie the sensitized material 14.

As the flanges are made of sheet metal, they will usually have a certain small 85 amount of resilience and there will be a tendency for them to be pressed outwardly under the pressure of the coiled material within, this being indicated in Fig. 5, where the dotted line indicates the normal position of the flange and the full line its position when strip material is wound on the spool, such material being also indicated in dotted lines. The amount of this distortion is exaggerated in this figure, and it is only necessary that there be a resilient coaction between the paper and the spool flange. 90

It will be understood that when I use the term "margin" or "marginal portion," I refer to a limited area or border adjacent the edge as distinguished from the edge itself. 105 It is desirable that the marginal abutment shall be continuous, so that there shall be an unbroken light seal at all points of the cir-

cumference of the ends of the rolled material.

While I have shown certain forms of my invention, it is obvious that numerous other 5 embodiments are possible and I contemplate as included in my invention all such equivalents and modifications as fall within the scope of the appended claims.

Having thus described my invention, what 10 I claim as new and desire to secure by Letters Patent is:

1. A spool for photographic film comprising a core with spaced circular flanges, at least one of said flanges being resilient 15 and having at its margin and on its inner surface an inwardly projecting continuous ring.

2. A spool for photographic material comprising a core and end flanges rigid there- 20 with, the flanges having on their facing surfaces inwardly projecting rings extending continuously around their entire margins, said rings being gradually inclined toward the core in directions away from one an- 25 other.

3. A spool for photographic film comprising a core and resilient end flanges, the flanges being inclined inwardly toward each other to form inwardly projecting rings ex- 30 tending continuously around their entire margins.

4. A spool for photographic film comprising a core and circular end flanges, the flanges having on their facing surfaces in- 35 wardly projecting rings extending continuously around their entire margins, said rings being inclined in directions away from one another both toward the core and toward the edges of the flanges, so that strip photo- 40 graphic material may be readily rolled upon and unrolled from said spool.

5. A spool for photographic film compris-

ing a core and circular end flanges, the flanges having on their facing surfaces in- 45 wardly projecting rings extending continu- 50 ously around their entire margins, said rings being gradually inclined toward the core in directions away from one another, and being more sharply inclined toward the edges of the flanges in directions away from one another.

6. A spool for photographic film comprising a core and circular end flanges, the inner surfaces of the end flanges from the core to points adjacent the edges of the 55 flanges inclining gradually and continuously toward each other to continuous rings of uniform maximum displacement from the planes of the central portions thereof, said rings extending around the margins of the 60 flanges.

7. A spool for photographic film comprising a core and circular end flanges, the inner surfaces of the end flanges from the core to points adjacent the edges of the 65 flanges inclining gradually toward each other to rings of uniform maximum displacement from the planes of the central portions, and then recurring to form rounded surfaces upon the outer sides of 70 said rings.

8. A spool for photographic film comprising a metal core and flanges of resilient sheet metal rigidly attached to the ends of said core, and forming a light-tight connection therewith, the flanges inclining gradually from said core to points adjacent the edges of the flanges to form continuous in- 75 wardly projecting rings and recurved to form rounded surfaces upon the outer sides 80 of said rings.

Signed at New York this 29th day of August, 1921.

EDWIN F. KINGSBURY.
